UNITED STATES PATENT OFFICE

JOHN W. CANNON, OF PLAINFIELD, NEW JERSEY

HEATER FOR BOILERS OF THE HORIZONTAL TYPE

Application filed November 14, 1928. Serial No. 319,387.

This invention relates to heaters, and more particularly to water heaters of the house-heating boiler type.

It is the general purpose and object of the invention to provide a heater of the character referred to which will secure a very high efficiency from the combustible fuel, thereby resulting in economy of operation. A further object of the invention is to provide a construction of heater which, while realizing such efficiency and economy in operation, is extremely simple in construction and economical of production.

Further objects of the invention will appear hereinafter and will be realized in and through the construction and arrangement of parts shown in the drawings, wherein Fig. 1 represents a central vertical sectional view through a heater constructed in accordance with my invention; Fig. 2 a horizontal sectional view corresponding to the line 2—2 of Fig. 1 and looking in the direction of the arrows; Fig. 3 a vertical sectional view corresponding to the line 3—3 of Fig. 1 and looking in the direction of the arrows; Fig. 4 a view, similar to Fig. 1, showing a modified form of heater embodying my invention; Fig. 5 a horizontal sectional view corresponding to the line 5—5 of Fig. 4 and looking in the direction of the arrows; and Fig. 6 a vertical sectional view corresponding to the line 6—6 of Fig. 4 and looking in the direction of the arrows.

Referring first to Figs. 1 to 3 inclusive, 15 denotes the bottom wall, 2 the side walls, 3 the top and 4 and 5 the front and rear walls, respectively, of a boiler of the section-type. The boiler shown in both forms of my invention is preferably rectangular in horizontal and vertical section. It is provided with a firebox A, the said firebox comprising a bottom wall 6, which extends from the front to the rear of the boiler and is spaced from the bottom wall of said boiler; with side walls 7, 45 which extend above the water space in the boiler; and with front and rear walls constituted by the front and rear walls 4 and 5 of the boiler. The top of the firebox comprises an upper horizontal wall 8 which extends the full length of the heater, merging

at its ends with the front and rear walls thereof and from the front of which there extend vertical flues 9 communicating with rearwardly extending side flues 10, the rear ends of which communicate with the forwardly extending flue 11 which discharges into a stack 12.

Mounted in the lower portion of the firebox is a combustion chamber comprising a bottom wall 13 and a top wall 14. The bottom wall is supported on lugs 15^a projecting inwardly from the sides 15, intermediate the top and the bottom of said sides. The top wall 14 is provided with grooves 14^a by which it is seated on top of the side walls. A combustion passage 16 is formed within and between the parts 13, 14 and 15. The rear of the bottom wall extends upwardly, as shown at 13^a, as far as the top 14, and forms with the rear end of said top an outlet 17 for products of combustion.

The parts 13^a, 14 and 15 are composed of refractory material having a thermal conductivity in excess of 0.006 calorie/cm.³/sec./°C., examples of such materials being silicon carbide (conductivity .034 units) and fused alumina (conductivity .010 units). Silicon carbide is particularly suitable as in addition to its high thermal conductivity it possesses an emissivity which has been found to be approximately 97% of that of black bodies, rendering it particularly well fitted to transmit heat by radiation to the metal walls of the water jacket of the furnace. Its properties also cause the walls of my combustion chamber when built of this material to maintain a comparatively uniform temperature with a consequent even and more efficient distribution of heat to the water boiler with minimum damage to the iron walls.

The front of the bottom wall is spaced from the front of the heater, providing an inlet port 18 to the combustion chamber around the front end of the bottom thereof. It will be noted that the lugs or ledges 15^a support the bottom 13 above the bottom 6 of the firebox, there being a horizontal flue 19 provided between the parts 6 and 13, the inlet to which flue is formed by an opening 20^a in a door 20 which closes the rear of the space

between the walls 6 and 8 of the firebox.

The air inlet opening 20^a is controlled by a damper 21 which is operated by an arm 22 and a chain 23 from a thermostat (not shown) which thermostat is adapted to operate a motor in a casing 24 through the conducting wires B and C in a manner well known to those skilled in the art. The thermostat will be installed in the particular place the temperature whereof is to operate the damper. Instances of thermostatically controlled mechanisms such as indicated herein are the "Honeywell" control and the control known to the trade as the "Regi-therm."

25 denotes a gas supply pipe which projects through the door 26 which closes the front of the space between the walls 6 and 8, the said pipe discharging into a header 27 provided with a horizontal series of burner nozzles 28. The supply of gas to the header 27 is shown as controlled by a slow moving valve 29 (such as is described in copending application Serial No. 321,254, filed Nov. 22, 1928) which may also be operated by means of a motor, indicated generally at 30, and conductors D and E leading to a thermostat (not shown) which is located in the particular place the temperature of which is to control the supply of gas to the burner. Control member 30 may be identical with member 24 but is shown separately for convenience in drawing.

With the parts constructed and arranged as described, the burners 28 will be lighted by means of a pilot burner such as is indicated by 61 in Fig. 1 or 61' in Fig. 4, and air to support the combustion of the gas will be supplied through the inlet 20^a, flue 19, and port 18, where it will mingle with the gas and be burned in the flue or pass 16. The arrangement of the port 18 and of the burner nozzles 28 is such that the air will be entrained by the gas issuing from said nozzles and mingled with such gas in such proportion as to enable the gas to be consumed within the combustion space or passage 16.

The walls 13, 14 and 15, being made of the material specified, will radiate heat resulting from combustion to the flue 19, thereby securing great efficiency in the combustion of the mixture of gas and air within the flue or pass 16. By locating the burner header 27 in the front of the combustion chamber and above the port 18, the gas is preheated in such header prior to its combustion, both by the heated air delivered through said port and by the heat in the combustion chamber.

The burning gases and products of combustion pass through the port 17 into the rear of the upper portion of the firebox, whence they flow forwardly through the flue 31 formed between the parts 7, 8 and 14, and the products are then delivered through the vertical flues 9 into the rearwardly extend-

ing flues 10 and thence into the forwardly extending central flue 11.

By reason of the construction and arrangement of parts, the air in the flue 19 and the products of combustion and gases in the flue 31 will be heated by radiation from the combustion chamber, as will also the water in the adjacent portions of the boiler. The arrangement of the flues 10 and 11 insures the heating of the vapors evolved from the water in the boiler.

In Figs. 4 to 6 there is shown a modification of my invention wherein the boiler proper is substantially identical with that shown in Figs. 1 to 3; and corresponding parts of the boilers in both forms are designated by the same reference characters. In the second form, however, the combustion chamber is of the "two-pass" type and comprises a bottom wall 32, a top or cover wall 33, and side walls 34 provided with ledges 34^a which support a partition 35 extending rearwardly from the door 23 toward but spaced from the rear wall 36, thereby to provide a passage 37 around the rear of the said partition. The top of the combustion chamber is provided adjacent to the front of the boiler and the door 26 with a flue or outlet 38 by which the products of combustion are discharged into a horizontal flue 39, whence they pass through vertical flues 40, adjacent the rear of the boiler, into forwardly extending side flues 41 which communicate at their front ends with a front transverse flue 42 which in turn communicates with a central rearwardly extending horizontal flue 43, the last mentioned flue discharging into the stack 44.

The front of the flue 38 is formed by a transverse slab 38^a which rests on top of the partition 35. The walls 32-38^a inclusive are made of material having very high heat transmitting qualities at high temperatures, silicon carbide for example, having a thermal conductivity greater than 0.006 calorie/cm.³/° C./sec., as is the case with the material employed for the combustion chamber in the form of my invention shown in Figs. 1 to 3 inclusive.

The door 26 is provided with a transverse opening 26^a above the wall 32 and below the partition 35 and extending preferably nearly the full width of the lower pass of the combustion chamber. Projecting outwardly from this opening is a casing 45 which casing, in vertical section, is in the form of a Venturi tube. A gas supply pipe 46, which is provided with a slow opening valve 47, such as is described in the copending application referred to, delivers gas to a header 48 arranged in front of the outer end of the casing 45. From this header, burner tubes 49 project axially into the casing 45, each tube being provided with a flattened delivery end 49^a each having an elongated delivery slot 50. The slots 50 are arranged adja-

cent to the contracted portion of the Venturi tube casing 45, this arrangement insuring an efficient entraining by the gas of the air supplied to the outer end of the casing, whereby 5 sufficient air will be admixed with the gas to enable the mixture to be consumed in the combustion space formed by the flues below, above and around the partition 35.

The valve 47 may be operated by a thermostatic 10 (not shown) installed in the particular place the temperature whereof is to control the supply of gas to the header. 51 indicates conventionally a thermostatically operated control for the valve, the said control 15 being provided with wires 52 and 53 leading to the thermostat.

The supply of air to the Venturi tube casing is controlled by a pair of dampers 54 operated by arms 55 connected to a link 56, the 20 link and arms in turn being connected by a chain 57 to a thermostatically operated control indicated generally at 58, the wires 59 and 60 leading from said control to the thermostat (not shown). As pointed out in connection 25 with the form of my invention shown in Figs. 1 to 3, any standard or suitable type of thermostatically operated control mechanism may be employed.

With the parts constructed and arranged 30 as shown in Figs. 4 to 6, the operation will be as follows: Gas will be supplied to the pipe 46 in the usual manner and from there through the slow opening valve 47 to the header 48 where it is preheated after which 35 the gas passes into the combustion chamber where it is ignited as it emerges from the slots 50. The streams of gas, being delivered at the contracted portion of the Venturi tube casing, will entrain in a most efficient manner 40 the air supplied to the front of said chamber, and the ignited mixture will be burned in the combustion chamber. The parts will be so proportioned and constructed that complete combustion is preferably obtained within the 45 chamber, the best results being accomplished when the end of the flame reaches the port 38. The water within the boiler will be heated in a very efficient manner by radiation from the combustion chamber and from the walls 50 of the firebox; while the arrangement of the flues 41 and 43 insures efficient heating of the vapors evolved from the water in the boiler.

A principal advantage of my fuel burning arrangement is that it secures substantially 55 complete combustion of the fuel at all times. Perfect combustion is particularly hard to obtain when a large flow of gas is turned on while the combustion chamber is cold. This is because in such cases the rate of combustion 60 in the cold combustion chamber is so low that the oxidation of the gas is not complete, and a heavy deposit of soot is formed within the combustion chamber. I avoid this trouble however, by admitting only a 65 limited amount of gas until such time as the

interior of the combustion chamber has been heated to incandescence after which a greatly increased rate of gas flow is permissible.

This adjustment of the rate of gas flow to produce complete combustion at all times is obtained by the use of a slow opening valve 70 which permits the initial gas flow to the combustion chamber to be maintained at a rate which is a small fraction of the rate after the valve has been fully opened. In this way complete combustion of the gas is secured at all times. After the walls of my combustion chamber have been heated to incandescence, it is possible to secure complete combustion of 75 gas in the chamber at a very high rate due to the accelerated velocity of oxidation at high temperatures and the speed with which heat liberated within the combustion chamber is transmitted through the wall and radiated to the water containing casing.

While my invention has been described primarily with reference to a heater of water or steam, it is also obviously adaptable to a wide variety of other uses, and its broader aspects should not be considered as limited to the specific purpose illustrated.

Having thus described my invention, what I claim is:

1. An apparatus of the character described comprising a boiler casing having a substantially horizontally extending firebox therein, a horizontally extending combustion chamber in said firebox, the firebox being so situated as to transmit heat by radiation to the inner wall of the casing and thence by conduction to the water below and around it, the said combustion chamber comprising upper and lower walls and side walls providing a combustion space therebetween, there being a flue for supplying air to one end of the combustion chamber, the said flue being located between the bottom of the combustion chamber and the bottom of the firebox and communicating with one end of the combustion chamber by a port, the walls of the combustion chamber being comprised of silicon carbide whereby the heat is easily conducted to the incoming air in said flue and radiated through the incoming air to the adjacent water walls, a burner above such port arranged to discharge into the combustion chamber, there being a flue above the combustion chamber and communicating therewith by a port at the end of the chamber opposite the burner, and flues extending longitudinally of the 100 heater above the liquid-containing space therein and adapted to receive products of combustion from the second flue.

2. An apparatus of the character described comprising a boiler casing, a firebox within the casing and extending longitudinally and horizontally thereof, the lower portion of the firebox extending into the liquid in said casing and the upper portion of the firebox communicating at one end with horizontally ex- 105 110 115 120 125 130

tending flues located in the vapor-containing space of the boiler, a combustion chamber in the lower portion of the firebox and extending substantially parallel with the bottom thereof and providing between the bottom of the combustion chamber and the bottom of the firebox a horizontal flue for supplying air to the combustion chamber through a port at one end of the bottom of said chamber, the walls of the combustion chamber being composed of silicon carbide whereby heat is conducted in large quantities to the incoming air in said flue and is also radiated in large quantities to the water in the lower part of the casing, and a burner located above the said port and arranged to discharge into the combustion chamber, there being a flue between the top of the combustion chamber and the top of the firebox and communicating with the combustion chamber through an outlet located at the opposite end of the chamber from said burner, the end of the last mentioned flue which is opposite the said outlet communicating with the flues in the vapor space.

3. An apparatus of the character described comprising a horizontally extending boiler casing, a horizontally extending firebox in said casing and having its lower portion submerged in the liquid therein and spaced from the adjacent walls of the boiler casing, a combustion chamber of high heat-radiating material located in the lower portion of the said firebox and extending substantially from one end to the other thereof, and means for delivering gaseous fuel to one end of said combustion chamber, there being a flue for air extending beneath the bottom of said combustion chamber in the said firebox for supplying air to the gaseous fuel burned therein, whereby the air to support combustion will be heated through the bottom wall of the combustion chamber, and the water in the lower part of the casing will be heated by radiation emitted from the bottom wall of the combustion chamber.

4. An apparatus of the character described comprising a horizontally extending boiler casing, a horizontally extending firebox in said casing and having its lower portion submerged in the liquid therein and spaced from the adjacent walls of the boiler casing, a combustion chamber of high heat-radiating material located in the lower portion of the said firebox and extending substantially from one end to the other thereof, means for delivering gaseous fuel to one end of said combustion chamber, there being a flue for air extending beneath the bottom of said combustion chamber in the said firebox for supplying air to the gaseous fuel burned therein, whereby the air to support combustion will be heated through the bottom wall of the combustion chamber, temperature controlled means for regulating the supply of air to the

said flue, and temperature controlled means for regulating the supply of gaseous fuel to said combustion chamber.

5. An apparatus of the character described comprising a boiler casing having a substantially horizontally extending firebox therein, a horizontally extending combustion chamber in said firebox, the walls of the combustion chamber being composed principally of material having high heat-radiating qualities at high temperatures, and having a thermal conductivity greater than 0.006 calorie/cm.³/° C./sec., doors closing the opposite ends of said firebox, one of the doors having an opening therethrough communicating with one end of the combustion chamber, the second door containing an adjustable inlet for air to be preheated by passage under the lower wall of the combustion chamber in a direction opposite to the flow of the adjacent combustion gases, an air duct leading from the adjustable opening in the other door and lying between the floor of the radiating combustion chamber and the bottom wall of the firebox, and means for delivering fluid fuel through said opening into said combustion chamber.

6. An apparatus of the character described comprising a boiler casing, a firebox within the casing and extending longitudinally and horizontally thereof, a combustion chamber in the lower portion of the firebox and providing, between the bottom of the combustion chamber and the bottom of the firebox, a horizontal flue for supplying air to the combustion chamber through a port at one end of the bottom of said chamber, the fire box being so situated as to transmit heat by radiation to the inner wall of the casing and thence by conduction to the water below and around said casing, a burner header in the said combustion chamber located above the said port and arranged to discharge gaseous fuel into the combustion chamber, the said combustion chamber being composed principally of material having high heat-radiating qualities at high temperatures, and having a thermal conductivity greater than 0.006 calorie/cm.³/° C./sec., whereby air supplied through the said flue will be heated and the gas in the burner header will be heated by such air and by the heat within the combustion chamber, while the water in the lower part of the casing is heated by radiation from the bottom wall of the combustion chamber.

7. An apparatus of the character described comprising a boiler casing having a substantially horizontally extending firebox therein, a horizontally extending combustion chamber in said firebox, the walls of the combustion chamber being composed principally of material having high heat-radiating qualities at high temperatures, and having a thermal conductivity greater than 0.006 calorie/cm.³/° C./sec., doors closing the opposite ends of said firebox, one of the doors having an opening

therethrough communicating with one end of the combustion chamber, a burner in the end of the combustion chamber adjacent the said opening and receiving gaseous fuel through 5 said opening, there being a flue between the bottom of the combustion chamber and the bottom of the firebox for supplying air to the combustion chamber and said combustion chamber having below the said burner a port 10 for admitting such air, whereby the gas supplied from said burner is preheated by such air and by the combustion within the combustion chamber, and the water in the lower part of the casing will be heated by radiation 15 emitted from the bottom wall of the combustion chamber.

8. An apparatus of the character described comprising a horizontally extending boiler, a horizontally extending firebox mounted in 20 said boiler and extending substantially the full length thereof and having its walls spaced from the boiler casing and its lower end submerged in the liquid in said casing, a combustion chamber having thin walls of 25 high thermal conductivity and high heat radiating qualities mounted in the firebox and extending substantially from the front to the rear thereof, the walls of said combustion chamber being arranged in proximity to the 30 side walls of the firebox, a burner arranged to discharge into one end of said combustion chamber, means for conveying fluid fuel to said burner, a slow opening valve having thermostatic control for regulating the rate of flow 35 of fuel to the burner to prevent accumulation of soot therein, and a flue extending beneath the bottom of said combustion chamber for supplying preheated air to the fluid fuel burned therein.

40 In testimony whereof I affix my signature.
JOHN W. CANNON.
